Primary Examiner — Cathy Anne MacCormac*(74) Attorney, Agent, or Firm* — Strategic Patents, P.C.(57) **CLAIM**

What is claimed is the ornamental design for a three-dimensional printer frame, as shown and described.

DESCRIPTION

FIG. 1 is a front perspective view of a design for a three-dimensional printer frame.

FIG. 2 is a left side view of the design.

FIG. 3 is a right side view of the design.

FIG. 4 is a front view of the design.

FIG. 5 is a back view of the design.

FIG. 6 is a top view of the design; and,

FIG. 7 is a bottom view of the design.

The broken lines showing portions of the three-dimensional printer frame are for illustrative purposes only and form no part of the claimed design.
